(57) **CLAIM**

The ornamental design for a transaction card with label, as shown and described.

DESCRIPTION

FIG. 1 is a top rear perspective view of a transaction card with label showing the claimed design;

FIG. 2 is a rear view thereof;

FIG. 3 is a front view thereof;

FIG. 4 is a top view thereof;

FIG. 5 is a bottom view thereof;

FIG. 6 is a left side view thereof; and,

FIG. 7 is a right side view thereof.

The broken lines in the figures show portions of the transaction card, label, or environment that form no part of the claimed design.

The figures are illustrated to show contrasting appearance.

1 Claim, 5 Drawing Sheets See application file for complete search history.
